MOUTHPIECE SENSOR FOR SPIROMETER MEDICAL APPARATUS

Bernard N. Gray, 135 Parkwood Drive, East Pepperell,
Mass. 01437, and John W. Burke, 34 E. Wyoming
St., Melrose, Mass. 02176

Filed Mar. 20, 1974, Ser. No. 452,815

Term of patent 14 years

Int. Cl. D24—01
U.S. Cl. D83—1 F

Fig. 2.

Fig. 3.

Fig. 4.

FIG. 1 is a perspective view of a mouthpiece sensor for a spirometer medical apparatus embodying our design;

FIG. 2 is a side elevational view of the mouthpiece sensor depicted in FIG. 1;

FIG. 3 is an end view of the mouthpiece sensor shown in FIG. 1; and

FIG. 4 is a view from the other end of the mouthpiece sensor.

We claim:

The ornamental design for a mouthpiece sensor for spirometer medical apparatus, substantially as shown.
